Kitagawa et al., U.S. Design Application entitled "Fluorescent Lamp," U.S. Appl. No. 29/286,978, filed May 24, 2007.

Primary Examiner—Freda S. Nunn*Assistant Examiner*—Kevin K. Rudzinski(74) *Attorney, Agent, or Firm*—Brinks Hofer Gilson & Lione**(57) CLAIM**

We claim the ornamental design for a fluorescent lamp, as shown and described.

DESCRIPTION

FIG. 1 is a front perspective view of a fluorescent lamp of the present invention;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

The broken line showing of fluorescent lamp is included for the purpose of illustrating environment and forms no part of the claimed design.
